STABILATOR FOR BEDSPRINGS

Thomas S. Foley, Utica, N. Y., assignor to Foster Brothers Manufacturing Company, Utica, N. Y., a corporation of New York

Application May 20, 1940, Serial No. 336,079

2 Claims. (CL 5—262)

My present invention relates to bed springs of the type where a plurality of compression springs are disposed between an upper and a lower border frame.

The purpose of this invention is to provide a construction of the class described where means are provided for preventing horizontal vibration of the upper frame relative to the lower frame, and yet allowing full freedom for the upper frame to move towards the lower frame when the spring is compressed.

A further purpose is to provide a new and improved stabilator of the type above mentioned, which stabilator is economical in construction, efficient, durable and noiseless in operation and not liable to get out of order.

In bed springs of the type mentioned, due to the extreme flexibility of the whole series of compression springs, the upper frame can vibrate horizontally, usually from side to side of the bed spring. This "float" horizontally is very undesirable and displeasing to the occupant of the bed. Such vibration can start on very slight movement of the occupant of the bed and continues for several lateral movements, since there is nothing in the ordinary plain bed spring of this type to definitely bring such vibrations to an end. It is the main purpose of this invention to provide a construction that will satisfactorily control such lateral "floating" movement and prevent such horizontal or lateral vibration. I have called this device a stabilator, as distinct from the heretofore often used stabilizers, which are devices for making the upper frame of a bed spring move up and down in a vertical line. My stabilator is not intended to and does not compel the upper frame to move up and down in a vertical direction, but does cause the upper frame to move downwardly on a slight curve with a relatively long radius, which causes so slight a sidewise movement as to be unnoticeable but does prevent vibration laterally or in a horizontal direction.

A still further purpose of my invention is to provide a stabilator of such construction and operation and cooperation with the two border frames of the bed spring that even the slight lateral movement occurring when the bed spring is compressed causes movement in opposite directions at the opposite ends of the bed spring and thus substantially neutralizes even this slight sidewise movement through the middle of the bed spring between its two ends.

Further purposes and advantages of my invention will appear from the specification and claims herein.

Fig. 1 is an end elevation of a bed spring equipped with stabilators embodying my invention. Most of the compression springs are omitted from the drawings in order to more clearly show

the stabilator link at the farther end of the bed spring.

Fig. 2 is a view similar to Fig. 1 when the upper frame has been compressed towards the lower frame, and showing the upper frame moved to the left hand side slightly, relative to the lower frame.

Fig. 3 is a vertical sectional view on line 3—3 of Fig. 1 but on a considerably enlarged scale.

Fig. 4 is a plan view of a bed spring embodying my invention, the springs and the spring-supporting members upon the upper and lower border frames being omitted in order to more plainly show the border frames, the upper border frame being shown in dash lines to illustrate its position when the bed spring is compressed.

Fig. 5 is an enlarged vertical sectional view on line 5—5 of Fig. 4, of the joint between the upper end of the stabilator link and the adjacent portion of the rod forming the upper frame.

Fig. 6 is a side view of the construction shown in Fig. 5, as seen from the outside of the bed spring.

Referring to the drawings in a more particular description it will be seen that the bed spring illustrated is of the conventional type including a lower border frame 10, an upper border frame 11, a plurality of interposed vertically arranged compression springs 12 supported at their lower ends and held in place at their upper ends by conventional spring-supporting members 13 carried by the lower and upper border frames 10 and 11. The lower border frame is commonly formed of angle iron either as different lengths thereof fastened together at the corners or as a continuous length thereof encircling the whole frame. Ordinarily the horizontal web 14 of the angle iron lower frame is disposed at the top of the frame and utilized more or less as the direct support of the lower ends of the compression springs along the borders of the bed spring. The lower frame 10 is provided with a plurality of ordinarily crosswise extending bands or strips 15 to support in any desired manner the lower ends of the springs 12 that are inside of the lower frame. Commonly on bed springs of this type narrow metal bands 16 are used extending crosswise of the bed spring and connecting the middle portions of the springs 12. Commonly 50 also longitudinally extending wires 17 connect the cross bands 16 and the central portions of the springs in the longitudinal rows.

The upper frame 11 may consist of a lighter form of angle iron forming in one continuous strip, as in Figs. 1 and 2, both the sides and ends of the frame, or the upper border frame may consist simply of a continuous strong wire or rod 31, as in Figs. 4 and 5.

Ordinarily the means for supporting and holding the upper ends of the springs 12 are links

or small helical springs connected to laterally extending and longitudinally extending bands either of metal or webbing or any combination thereof, which intersecting bands form the mattress supporting surface and are suitably attached at their ends to the upper border frame 11. The upper ends of the border springs may be directly attached by suitable means to the upper border frame. A more detailed description of the filling of the bed spring or of the supports for the compression springs, and of the structure of the mattress-supporting surface, is not deemed necessary, as the details thereof may vary and those parts do not constitute any part of this invention.

Ordinarily the upper border frame 11 is larger than the lower border frame 10, and the upper border frame projects beyond the lower frame all the way around the bed spring.

Along each of the two opposite ends of the two border frames I place a connecting link 21. One end of each of these links is pivoted to or operatively pivoted to the lower border frame and the other end of the link is pivoted to or operatively pivoted to the upper frame along that edge of the bed spring. These two connecting links 21 will be placed at the opposite ends of the bed spring as that arrangement is necessary for neutralizing lateral vibration. Lateral vibration or side sway is much more common than lengthwise sway and more displeasing to the occupant of the bed than lengthwise sway or vibration.

Ordinarily the connecting links cannot be pivoted directly to the lower border frame and usually not even to the upper border frame, the reason for this being that in ordinary bed springs of this type the lower border frame is used to provide a direct support for the lower and smaller ends of the compression springs 12 along the border of the bed spring. The upper ends of these springs are usually much larger than the lower ends, thus obviously requiring the upper border frame to be on a line farther out than the lower border frame. Notwithstanding this arrangement of the upper border frame being farther out than its corresponding portion of the lower border frame, I provide an operative pivoted connection between corresponding ends of the two frames by providing an angle bracket 22 for securing the lower end of each link to a portion of the lower border frame. The horizontal arm 23 of this bracket 22 is placed flat against the upper surface of the horizontally arranged web 14 of the angle iron shaped lower cross frame 10 and fastened thereto as by rivets 25. The upstanding arm 26 of the bracket 22 projects upward from near the outer edge of the horizontal web 14 of this part of the lower frame 10.

Preferably as shown in Fig. 3, the lower end of the connecting link is located outside of the upright arm 26 of the angle bracket 22 and pivoted thereto as by a shouldered rivet 28, placed with its head to the outside of the link 21 with an annular washer 29 placed beneath the head of said rivet or to the right thereof, as the parts are seen in Fig. 3. The relatively larger portion of the shank of this rivet projects through a suitable hole provided near the lower end of the link 21 and to the inside of the link there is placed about the said large portion of the shank of the rivet another annular washer 31. Just beyond this washer 31 the inner portion of the shank of said rivet is of definitely smaller diam-

eter, producing the desired shoulder 33. This shoulder faces inwardly and is adapted to directly engage the outer surface of the outer upturned arm 26 of said angle bracket. The inner extremity of the rivet is headed over against the inner face of the said upstanding arm 26 so as to rigidly fasten said rivet in place without pinching the link 21 against either the head of the rivet or the upstanding arm 26 of the bracket. The washers 29 and 31 are placed on the rivet to insure the easy pivoting action of the link 21 upon the pivot 30 without friction and without noise.

The link 21 is bent slightly outwardly soon after it leaves the upstanding arm 26 of the angle bracket 22, and towards its upper end the link is bent inwardly to a vertical plane so as to be parallel with the vertical portion that is pivoted to the upstanding arm 26 of bracket 22. In this way the upper end of the link is offset the proper amount outwardly to let its upper end be pivoted directly to the downhanging web of the upper frame, as shown in Fig. 3, where an angle iron form of upper web is used, or so as to be operatively pivoted to the upper frame where that frame is simply a round rod, as hereinafter described more in detail.

As is suggested in Figs. 1, 2 and 3, the upper border frame may be also composed of an angle-iron shaped member. The upper end of the link 21 will be pivoted thereto preferably by means of a shouldered rivet 34, substantially as described for the shouldered rivet 28 used at the lower end of this link, and so not needing to be further described herein. Preferably as shown in Fig. 3 however, the upper end of the link 21 will be mounted upon the inner side of the vertical down-hanging web 35 of the angle iron 36 used in this particular construction for the upper border frame. In this construction as shown in Fig. 3, the large original head 27 of this rivet 34 and the enlarged portion of the shank of this rivet will be at the inside of the web 35, so that the shoulder 30 of this shouldered rivet will be utilized against the inner side of the web 35 when the outwardly projecting extremity of the rivet is headed over against the outer face of said web to permanently fasten this rivet in place while still allowing an easy rotation of the link on said rivet. The usual annular washers of proper material will be placed at either side of the upper end of the link on the pivot, to prevent any noise in the action of the link.

In the bed spring shown in Fig. 4, the upper border frame 11 is indicated as being formed of a strong wire or round rod 37. Such round rod is not adapted in practice to have directly pivoted thereto the upper end of a connecting link 21, so I provide another form of bracket 38 to which the connecting link may be pivoted. This bracket, as seen in the enlarged vertical sectional view taken on line 5-5 of Fig. 4, is conveniently constructed of a length of suitable band iron and has its central portion closely wrapped around the rod 37, forming an almost complete ring 39, and the ends 40 and 41 of this ring are brought flat together and project away from the rod 37 more or less as shown in Fig. 5. These two ends are permanently fastened together by the shouldered rivet 42, the head 43 of which is shown to the inside or to the right as seen in Fig. 5 of the upper end of the connecting link 21, so that said link freely pivots on the enlarged shank portion of said rivet while the shoulder 44 of said rivet bears against the right hand outer face of the inner end

piece 41 of the bracket. Then when the outwardly projecting extremity of the rivet is headed over in the usual way the said pivot is rigidly fastened to the bracket 38. Then the portions of the strap, as at 45 (Fig. 6), forming the bracket between the rivet 42 and the rod 37 are punched or driven strongly together so as to even distort slightly the circle of the inclosed rod 37 as well as the said portions of the band iron forming the bracket. This operation binds the bracket so closely to the iron rod as to prevent sliding of the bracket on the rod and so tightly that any possible rotation of the bracket upon the rod is prevented. Preferably fabric washers will be placed at the opposite sides of the upper end of the link between the link and the head of the rivet and between the link and its bracket in order to prevent any possible noise from the metal parts at this joint.

It will be understood that the stabilizer links 21 are long relative to the cooperating parts of the bed spring so as to make the upper border frame, when compressed towards the lower border frame, travel through a very gentle curve. This is best seen in Figs. 1 and 2 where the stabilizer links 21 are operatively pivotally connected to the opposite ends of the bed spring. As will be seen in these views and as is the preferred construction, the said links have a length several times the distance between the two frames when they are not compressed together, or, stated in another way, the said links may be in length preferably at least about half the width of the bed spring. In Figs. 1 and 2 the near link 21 is pivotally fastened at its lower end to the bracket 22 upon the lower frame 10, and the upper and left hand end of the link is operatively pivoted to the upper frame 11. It will be obvious that as this bed spring is compressed, as by the weight of a person lying upon it, the upper border frame 11 will be caused to move slightly towards the left, as indicated by the dotted curved line going down from the center of the pivot at the upper end of the link 21. Due to the relatively long radius of the link 21 this curve, it will be seen, is very gentle and the sidewise movement, in normal use about one-fourth inch, and even on complete compression of the bed spring as for packing will be very slight, in practice only about five-eighths inch.

While this amount of side movement is so small as to be almost imperceptible to the occupant of the bed, I have constructed the preferred form of my invention in such a manner as to very largely neutralize even this slight amount of sidewise movement. I have accomplished this result by arranging the stabilizer links 21 at the opposite ends of the bed spring in reverse positions. This is best understood by observing Fig. 1 wherein, as already mentioned, I have described the near link 21 as operatively pivoted to its lower and right hand end to the lower frame 10, while the upper and left hand end of this near link is operatively pivoted to the upper border frame 11. The link 21 at the further end of this bed spring is operatively pivoted at its lower and left hand end to the lower frame 10 but its upper and right hand end is operatively pivoted to the upper frame 11. This reverse arrangement of the two stabilizer links is also plainly shown in Fig. 4

5 10 15 20 25 30 35 40 45 50 55 60 65 70

In this plan view the left hand end of the bed spring is the end shown in Figs. 1 and 2 of the drawings. As already explained and shown by a comparison of Figs. 1 and 2 the upper frame will move very slightly to the left as shown in Fig. 2. Accordingly when this bed spring is shown in plan view as in Fig. 4 the left hand end of the bed spring will have the left hand end of the upper border frame move slightly farther away while reversely the right hand end of the upper border frame 11 will move toward the observer. The relative position of the upper frame after such reverse movement at its two ends is diagrammatically shown on a somewhat enlarged and exaggerated scale by the dotted line position of the said upper frame. It will be obvious from the foregoing that by thus causing the opposite ends of the upper frame to move their slight amount in opposite directions when the bed spring is compressed, the amount of this sidewise motion will decrease as the longitudinal center of the bed spring is approached and that in fact at the central zone lengthwise of the bed spring there will be no sidewise motion. It will thus be seen that I have accomplished the further purpose of neutralizing even the slight sidewise movement incident to using the stabilizer links 21 as shown.

What I claim as new is:

1. In a bed spring, the combination of upper and lower border frames, spring supporting cross members on said frames, a plurality of vertically arranged compression springs disposed between said frames with their opposite ends secured to the cross members of said frames, a rigid connecting link at each end of the bed spring, each link having one end operatively pivoted to the upper frame and its other end operatively pivoted to the lower frame, the length of said links being approximately half the width of the bed spring so that lateral vibration of the upper frame relative to the lower frame is prevented but free movement of the upper frame towards the lower frame is allowed, said links being reversely arranged at the two ends of the bed spring so that on compression of the bed spring the lateral movement of the upper frame at the two ends of the bed spring is in opposite directions.
2. In a bed spring, the combination of upper and lower border frames, spring supporting cross members on said frames, a plurality of vertically arranged compression springs disposed between said frames with their opposite ends secured to the cross members of said frames, a rigid connecting link at each end of the bed spring, each link having one end operatively pivoted to the upper frame and its other end operatively pivoted to the lower frame, the length of said links being considerably greater than the distance between the frames when the bed spring is not compressed, so that lateral vibration of the upper frame relative to the lower frame is prevented but free movement of the upper frame towards the lower frame is allowed, said links being reversely arranged at the two ends of the bed spring so that on compression of the bed spring the lateral movement of the upper frame at the two ends of the bed spring is in opposite directions.

THOMAS S. FOLEY.
